(57) **CLAIM**

The ornamental design for a farrier's trimming and finishing aid, as shown and described.

DESCRIPTION

FIG. 1 is a top perspective view of a farrier's trimming and finishing aid showing my new design, the broken lines shown are for illustrative purposes only and form no part of the claimed design;

FIG. 2 is a side elevational view thereof;

FIG. 3 is a top plan view thereof; and,

FIG. 4 is a bottom plan view thereof.
